PEN CONTROL MECHANISM FOR PAPER
RULING MACHINE

Robert J. Thompson, Harrisburg, Pa., assignor to
The W. O. Hickok Mfg. Co., Harrisburg, Pa., a
corporation of Pennsylvania

Application March 2, 1944, Serial No. 524,766

4 Claims. (Cl. 33—39)

1

This invention relates to a pen control mechanism for paper ruling machines.

In the paper ruling art, it is the conventional practice to connect a plurality of pens to a pen beam and to supply ink to such pens to rule lines on paper sheets fed through the machine beneath the pens. The spacing of the lines, of course, is determined in accordance with the positions of the pens along the pen beam, which extends transversely of the direction of movement of the paper. In struck line ruling, it has been the common practice to provide cam means engageable with an arm connected to a pivoted pen beam support to move such arm upwardly and lift the pens from the paper at the point where the ruled lines are to terminate. The pens are biased downwardly toward the paper to move into engagement therewith after the arm is released by the cam means.

The biasing means employed for tending to move the pens into engagement with the paper is in the form of a spring or springs. These springs, in order to swing the pens into engagement with the paper, must overcome the inertia of the pens, the pen beam and the various elements connected thereto. As a result it has been found, as efforts have been made to increase the speed of production of machines of this character, that the biasing springs have a given maximum speed with which they can properly move the pens into engagement with the paper. The production speed of the entire machine is thus limited in accordance with the speed of operation of the biasing springs referred to.

An important object of the present invention is to provide an improved pen beam swinging means whereby the limitations of the spring means referred to are overcome, thus permitting a substantial increase in the speed of production of a ruling machine.

A further object is to provide an apparatus of this character wherein the cam means is utilized for positively moving the pens into engagement with the paper, thus permitting the starting points of the lines to be positively and exactly determined.

A further object is to provide novel motion transmitting means between the cam means and the pen beam support for effecting downward movement of the pens into engagement with the paper upon upward movement transmitted by the cams to the cam-engaging arm.

A further object is to provide such a mechanism wherein the motion transmitting means includes an element releasable from the cam-en-

2

gaging arm to permit upward movement of the pens from the paper when it is desired to render the apparatus inoperative, for example, when providing a different pen adjustment.

5 A further object is to provide a device of the character just referred to wherein the releasable element is so constructed as to provide either for the slight elevation of the pens from the paper independently of the cam operation, or to permit the pen beams to be swung to a substantial extent, when desired.

Other objects and advantages of the invention will become apparent during the course of the following description.

15 In the drawings I have shown one embodiment of the invention. In this showing:

Figure 1 is a fragmentary plan view of a portion of the apparatus showing the present invention,

20 Figure 2 is a vertical sectional view on line 2—2 of Fig. 1,

Figure 3 is a similar view on line 3—3 of Figure 1, parts being shown in elevation,

25 Figure 4 is a similar view on line 4—4 of Figure 1,

Figure 5 is a detail sectional view on line 5—5 of Figure 2, and

30 Figure 6 is a detail perspective view of the cam operated arm mechanism showing the parts separated.

Referring to the drawings the numeral 10 designates one of the side rails of the main frame of a paper ruling machine. Between such rail and the opposite corresponding rail (not shown)

35 a pen beam 11 extends transversely of the apparatus and is provided with a plurality of pens one of which is shown in Figure 1 and is generally indicated by the numeral 12. The pen beam and the pens carried thereby may be of any conventional type and form no part of the present invention per se, and it will be obvious that ink may be fed to the pens by any desired means.

Opposite ends of the pen beam are secured by screws 13 or any other suitable means to a horizontally extending pen beam supporting flange 14.

Each flange 14 is a preferably integral part of a pen beam support indicated as a whole by the numeral 15, and it will be obvious that one of these devices is employed at each side of the apparatus.

50 Each support 15 further includes a depending integral flange 16 lying against or adjacent the corresponding end of the pen beam 11, and the flange 16 carries a cylindrical projection 17 forming a conventional ball and socket to receive a ball 18 carried by a threaded stem 19.

preferably provided at its outer end with a knurled head 20. The threaded stem 19 extends through a cross head 21 adjacent one side thereof as indicated in Figure 1. The cross head 21 is vertically slidable in a guide structure 22 secured to the side frame 10. The top of the guide structure 22 is provided with a vertical adjusting screw 23 having a knurled head 24 at its upper end. This screw provides for vertical adjustment of the associated pen beam support 15. The threaded stem 19 provides for endwise adjustment of the pen beam. The stem 19 is adapted to be fixed in adjusted position by a jam nut 25 preferably having an operating handle 26 formed integral therewith.

The means for supporting the other end of the pen beam may be conventional, including a vertically adjustable cross head and a pen beam-supporting shaft rotatable in such cross head and slidable endwise upon adjustment of the stem 19. At the side of the apparatus shown in the drawings, the pen beam support 15 is provided with an upstanding integral lug 27 (Figures 2 and 4) to pivotally support an adjustable rocker 28. This rocker is provided intermediate its ends with depending lips 29 at opposite sides thereof and a screw or other pivot pin 30 extends through the lips 29 and through the lug 27. Thus the rocker 28 is supported by the pen beam support 15 and is adapted to turn on the axis of the pin 30. The rocker 28 is adapted to be fixed in adjusted positions. For this purpose screws 31 are threaded through the rocker 28 on opposite sides of the pivot 30 and have their lower ends engageable against the top of the flange 14. These screws are obviously adjustable to change the angular position of the rocker 28 relative to the support 15. Each screw 31 is provided with a jam nut 32 preferably of the same type as the jam nut 25. The upper ends of the screws 31 are provided with knurled heads 33 and one of these heads carries a ring 34 terminating in a hook 35 for a purpose to be described.

One end of the rocker 28 is provided with a projecting fork 36 and between the arms of this fork is arranged a rod or bar 37. A pivot pin 38 extends through the bar 37 and through the arms of the fork 36 and carries a nut 39 on one end thereof. The opposite end of the pivot member 38 carries an enlarged stud 40 seating against the adjacent fork arm 36. The arm 37 is provided in one face thereof toward its lower end with a relatively large notch 41 having a lower horizontal face 42, and below this notch is formed a second notch 43 having a lower horizontal face 44 for a purpose to be described.

The bar 37 carries a screw 42 to one end of which is connected a spring 43 and the other end of this spring is fixed as at 44 to the rocker 28. This spring obviously tends to swing the bar 37 in a clockwise direction about the pivot pin 38. This action renders the bar 37 normally automatically operative for performing its intended function as will be described later.

A supporting bracket indicated as a whole by the numeral 46 (Figures 2 and 3) is provided with a vertical depending portion 47 bolted as at 48 to the rail 10 of the main supporting frame. Beneath the pen beam 11, the bracket extends laterally as at 48 and then upwardly at an angle as at 49 (Figure 2) to terminate in a widened horizontal portion 50. The free end

of the bracket portion 50 is provided with a pivot pin 51 fixed to the bracket by a set screw 52.

An operating lever 54 is formed with a normally substantially horizontal portion 55 (Figures 2 and 6) intermediate the ends of which is formed an opening 56 (Figures 5 and 6) for rotatably receiving the pivot pin 51. This pin projects beyond the lever 54 and is surrounded by a torsion spring 57 one end of which is arranged in a slot 58 in the end of the pivot pin 51 and the other end of which engages beneath the horizontal portion 55 of the lever 54. The spring 57 tends to swing the operating lever 54 in a counterclockwise direction as viewed in Figure 2. The end of the lever 54 remote from the bar 37 turns downwardly as at 59 and terminates in a fork 60 rotatably supporting a roller 61 for a purpose to be described.

A small bracket 63 has one end secured to the top of the bracket arm 50 and has its other end 64 offset upwardly and extending transversely over the lever arm 55. A set screw 65 extends through the bracket arm 64 and is locked in position by a jam nut 66, preferably provided with an operating handle as in the case of each of the other jam nuts previously referred to. The set screw 65 contacts the lever portion 55 to the right of the pivot pin 51 (Figure 1) to limit swinging movement of the lever 54 in a counterclockwise direction. The adjacent end of the lever portion 55 terminates in an edge 67 which is normally arranged in the notch 41 in engagement with the horizontal face 42. It will be apparent that any upward movement of the roller 61 will swing the lever 54 in a clockwise direction to pull downwardly on the bar 37 and thus rock the rocker 28, support 15 and the pen beam in a counterclockwise direction as viewed in Figure 2.

This operation moves the pens into engagement with the paper. Means is provided for limiting such movement of the pen beam and the elements connected thereto. The stud 40 is provided with a set screw 70 threaded therethrough. This set screw is preferably provided with an upper knurled head 71 and a lower contact foot 72 engageable with the bracket portion 50. The set screw 70 is adjusted to limit turning movement of the rocker 28 at the point where the pens carried by the pen beam engage the paper. This positive limitation of turning movement of the pen beam is important since it permits swinging movement of the pen beam upon operation of the lever 54 without permitting the pens to strike the paper under undue pressure regardless of the speed of operation of the lever 54. Proper adjustment of the set screw 70 is maintained by a jam nut 73 also preferably provided with a convenient operating handle, as shown in Figure 3. The operation of the lever 54 is effected by cam means to be described and the parts are returned to normal position by a tension spring 74 connected at its upper end to the hook 35 and at its lower end to the bracket 46. Of course, the specific points of connection of the spring 74 are not important.

A shaft 76 extends transversely of the apparatus parallel to the pen beam and is supported in suitable bearings (not shown). This shaft carries a wheel 77 having an inner relatively deep groove 78 and an outer relatively shallow groove 79 extending around its periphery. Cam elements 80 are arranged in the groove 78 and similar but narrower cam elements 81 are ar-

ranged in the groove 79. Suitable set screws 82 are threaded into the wheel 71 to engage the cam elements 81, and similar but longer set screws 83 are threaded in the wheel 71 to engage and clamp the cam elements 80 in position. The arrangement of the cams permits relatively short arcuate cams to be employed in each of the grooves and to secure the effect of substantially longer cams, where needed, by arranging successive cams 80 and 81 with their ends in overlapping relationship. Both sets of cams engage the roller 61. It will be apparent that all of the outer edges of all of the cams will be concentric with the axis of the shaft 76 and of the same radius. Either of the cams 80 or 81 or two of such cams at the same time may engage the roller 61 to elevate the corresponding end of the lever 54 to swing the pen beam, as will be apparent. The shallow cam groove 79 permits the use of the set screws 83 radially inwardly of the groove 79, for engagement with the cam elements 80 as will be obvious.

The operation of the apparatus is as follows:

The ruling machine may be of any conventional type employing pen beams having pens carried thereby and suitably spaced according to the desired lining of the paper. The paper is fed automatically to the ruling machine by means synchronized with the driving of the shaft 76 and cam wheels 71. At the desired point with relation to the travelling of a sheet of paper, one of the cams 80 or 81 will engage the roller 61 to elevate the adjacent end of the lever 54. The opposite end of this lever, engaging the bottom of the notch 41, will pull downwardly on the bar 37 to transmit movement to the rocker 28 and through this element to the support 15 and pen beam 11 to swing these elements in a counterclockwise direction about the axis of the screws 19 as viewed in Figure 2. This operation positively swings the pens downwardly into engagement with the paper and inertia of the parts is prevented from overswinging the parts by engagement of the foot 72 of the set screw 70 with the upper face of the bracket portion 50. The point at which this movement will be limited will correspond to the position of the roller 61 at the top of the cam or cams in engagement therewith. The adjustment of the screw 70 is provided with the parts of the apparatus stationary and with the roller 61 on top of one of the cams and with the pens in proper engagement with the paper. With the parts so positioned, the jam nuts 32 (Fig. 2) may be loosened and the set screws 31 adjusted to swing the pen beam as may be necessary to properly engage the pens with the paper. The jam nuts 32 are then tightened and the pens will be in proper position with the roller 61 on top of one of the cams. Under such conditions the screw 70 may be turned downwardly until the foot 72 engages the bracket portion 50, whereupon the jam nut 73 may be tightened.

The operation referred to provides for positive and proper engagement of the pens with the paper. The operation is forced to take place positively in accordance with the operation of the cam mechanism and the pens accordingly engage the paper at exactly the right point at each cam operation.

As a cam, or a combination of two of the cams 80 and 81, pass beyond the roller 61, the spring 74 rocks the rocker 28, support 15 and the pen beam in a clockwise direction about the end screws 19 to return the parts to inoperative position until the next cam operation occurs.

The spring 74 may be relied upon to quickly move the pens from the paper at the proper point, it being necessary to effect only the slightest movement of the pen beam to disengage the pens. The operation of restoring the parts to normal position also effects upward movement of the bar 37 as the lever 54 turns in a counterclockwise direction. It will be apparent that the lever 54, rod 37 and pivot pin 38 constitute motion transmitting means between the cam or cams and the rocker 28 and the elements carried thereby. The latter elements turn on the axis of the end screws 19 while the lever 54 turns on the axis of the pivot pin 51. Accordingly the ends 67 of the lever 54 turns on one axis while the pivot pin 38 turns on a wholly different axis. However, the pivotal connection of the bar 37 permits relative movement of the point 67 and pivot pin 38 to take place without any disengagement of the parts. The spring 43 assists in maintaining the bar 37 in proper engagement with the lever 54, and the bar 37 turns slightly about the pivot pin 38 during the operations referred to.

If for any reason it is desired to render the pens inoperative while the apparatus is running, or at any other time, the upper end of the bar 37 (Figure 2) may be pulled to the left to release the lever end 67 from the notch 41, whereupon the rocker 28 and associated parts may rock in a clockwise direction about the axis of the screws 19 until the end 67 passes the bottom 42 of the notch 41. The upper end of the bar 37 then may be released, and further upward movement of the bar 37, as the member 28 rocks, will cause the lever end 67 to engage in the notch 43. Under such conditions the pen beam will have rocked to an inoperative position with the pens held above and out of engagement with the paper.

If it is desired for any reason to swing the pen beam to an even greater extent, the bar 37 may be moved again in the manner stated to release the lever end 67 from the notch 43, whereupon the pen beam and associated elements may swing as far as desired. If it is desired, a small stop 85 may be secured against one side of the rocker 28 with an end 86 extending across the rocker to be engaged by the bar 37, above the pivot 38. This engagement of the bar 37 with the stop end 86 will limit turning movement of the bar 37 in a clockwise direction as viewed in Figure 2, thereby positioning the curved lower end of the bar 37 for engagement with the curved end of the lever 54 which terminates in the end 67. Thus when the bar 37 is completely released from the lever 54 in the manner stated, the rocker 28 and associated parts may be swung back to an operative position and the two curved ends referred to will engage each other and swing the lever 37 so that the lower end thereof will properly pass over the lever end 67 to permit the latter to engage in either of the notches 41 or 43.

From the foregoing it will be apparent that the present device provides novel means for positively engaging the pens with the paper at the proper point. This eliminates any lag in the operation of the apparatus because of which present machines are limited in their speed of operation. The positive pen engaging operation of the present apparatus permits any conventional paper ruling machine to be operated at substantially higher speeds, thus requiring the use of fewer machines for a given plant capacity and substantially reducing costs involved in ruling

75 quantities of paper.

It is to be understood that the form of the invention herewith shown and described is to be taken as a preferred example of the same and that various changes in the shape, size and arrangement of parts may be resorted to as do not depart from the spirit of the invention or the scope of the subjoined claims.

I claim:

1. In a paper ruling machine having a pen beam movably mounted whereby a pen carried by said beam is movable into and out of contact with the paper, said beam being biased for movement to disengage the pen from the paper, a support positively connected to the beam, a rotary member having a cam, a lever pivotally supported intermediate its ends and having one end engageable by said cam to be operated thereby, and a motion transmitting connection having pivotal connection at one end with said support, said motion transmitting connection, at a point spaced from said pivotal connection, being notched to receive the other end of said lever whereby positive movement of the pen beam will be effected to move the pen into contact with the paper upon actuation of the first named end of said lever by said cam.

2. In a paper ruling machine having a pen beam provided with a paper ruling pen, means for supporting said beam for rocking movement on a horizontal axis parallel to the paper, said means including a support connected to the pen beam, means biasing said beam for rocking movement in one direction to disengage the pen from the paper, a cam rotatable on an axis parallel to the rocking axis of said beam, a lever pivotally supported intermediate its ends and having one end engageable by said cam to be positively operated thereby, and a motion transmitting element having pivotal connection with said support and being notched transversely of its length at a point spaced from such pivotal connection to receive the other end of said lever to positively transmit movement from said lever to said support to rock said pen beam in the opposite direction to move the pen into contact with the paper upon operation of the first named end of said lever by said cam.

3. In a paper ruling machine having a pen beam movably mounted whereby a pen carried by said beam is movable into and out of contact with the paper, said beam being biased for movement to disengage the pen from the paper, a rotary member having a cam, a lever mounted on

a fixed pivot intermediate its ends and having one end engageable by said cam to be operated thereby, and means for transmitting motion from said lever to said pen beam to effect positive movement of the pen beam to move the pen into contact with the paper upon actuation of the first named end of said lever by said cam, said means comprising a member adjustably connected to the pen beam and normally fixed relative thereto, and a motion transmitting element movably connected to said last named member and having a portion shaped for motion transmitting engagement with said lever, said motion transmitting element being movably connected to said last named member for movement out of engagement with said lever.

4. In a paper ruling machine having a pen beam movably mounted whereby a pen carried by said beam is movable into and out of contact with the paper, said beam being biased for movement to disengage the pen from the paper, a rotary member having a cam, a lever mounted on a fixed pivot intermediate its ends and having one end engageable by said cam to be operated thereby, and means for transmitting motion from said lever to said pen beam to effect positive movement of the pen beam to move the pen into contact with the paper upon actuation of the first named end of said lever by said cam, said means comprising a member adjustably connected to the pen beam and normally fixed relative thereto, a motion transmitting element movably connected to said last named member and having a portion shaped for motion transmitting engagement with said lever, said motion transmitting element being movably connected to said last named member for movement out of engagement with said lever, and means biasing said motion transmitting element into engagement with said lever.
